UNITED STATES PATENT OFFICE.

DANIEL APPEL, OF CINCINNATI, OHIO.

DESIGN FOR AN ECCENTRIC YOKE.

Specification forming part of Design No. 5,096, dated July 11, 1871.

To all whom it may concern:

Be it known that I, DANIEL APPEL, of Cincinnati, Hamilton county, Ohio, have invented and produced a new and original Design for an Eccentric Yoke.

The nature of my design is fully represented in the accompanying illustration, to which reference is made.

I claim as my invention—

The design for an eccentric yoke, as shown. In testimony of which invention I hereunto set my hand.

DANIEL APPEL.
